CLAIM

The ornamental design for a wireless remote control, as shown and described.

DESCRIPTION

Wireless remote control

1.1 : Perspective

1.2 : Front

1.3 : Back

1.4 : Right

1.5 : Left

1.6 : Top

1.7 : Bottom

The broken lines, and regions surrounded on all sides by broken lines, depict portions of the wireless remote control that form no part of the claimed design.

1 Claim, 7 Drawing Sheets(56)
